W. E. EGBERT.
KITCHEN CABINET.
APPLICATION FILED AUG. 11, 1915.

1,221,796.

Patented Apr. 3, 1917.

FIG. 3.

UNITED STATES PATENT OFFICE.

WILLIAM E. EGBERT, OF CLEVELAND, OKLAHOMA.

KITCHEN-CABINET.

1,221,796.

Specification of Letters Patent.

Patented Apr. 3, 1917.

Application filed August 11, 1915. Serial No. 44,976.

To all whom it may concern:

Be it known that I, WILLIAM E. EGBERT, a citizen of the United States, residing at Cleveland, in the county of Pawnee, State 5 of Oklahoma, have invented certain new and useful Improvements in Kitchen-Cabinets; and I do hereby declare the following to be a full, clear, and exact description of the invention, such as will enable others skilled 10 in the art to which it appertains to make and use the same.

This invention relates to improvements in cabinets.

One object of the invention is to provide a 15 rotary cabinet.

Another object is to provide a novel supporting leg for the rotary member of the cabinet.

Other objects and advantages will be apparent from the following description when taken in connection with the accompanying drawing.

In the drawing:

Figure 1 is an elevation of a kitchen cabinet and supporting leg, made in accordance with my invention,

Fig. 2 is a horizontal section on the line 2—2 of Fig. 1,

Fig. 3 is an enlarged vertical section 30 through the adjustable leg approximately on the line 4—4 of Fig. 1.

Referring to the accompanying drawing, and particularly to Figs. 1, 2, and 3, 10 represents the cylindrical casing of a kitchen 35 cabinet which has an opening 11 in one side and within which there are mounted the slidable doors 12. Within the casing is mounted a rotatable drum 13 having a plurality of canisters 14, drawers 15 and compartments 16. The upper and lower ends 40 of the drum 13 carry pintles 17, the upper one of which is engaged in a bearing 17' on the top of the casing.

The casing is placed on a table 18 in which 45 is bored an opening 19 to permit the passage therethrough of the lower pintle of the drum.

Beneath the table is disposed a post 20 having a suitable base 21. The upper end 50 of the post is formed with a socket 22 in which is disposed a large ball 23. A bolt 24 has a head 25 on its lower end formed

with a socket 26 which receives the upper portion of the ball 23, and adjustably engaged on the upper end of the bolt is a 55 sleeve 27 formed with a socket 28 in its upper end for the reception of the before-mentioned lower trunnion 17 of the drum, said sleeve bearing against the lower face of the table top to maintain said sleeve and bolt in 60 upright position.

Also mounted on the bolt below the sleeve, 27 is a lock nut 29.

It will thus be seen that the weight of the drum 13 is taken on the supporting leg, 65 and not on the top of the table, the lower pintle 17 rotating in the sleeve 27. The ball permits a more easy rotation of the bolt 24 when adjusting the same, especially with the great weight of the drum thereon. 70

What is claimed is:

1. The combination with the apertured top of a table, of a supporting leg for a rotating cabinet comprising a standard having a seat in the upper end, an anti-friction 75 bearing disposed in the seat, a vertical screw having a head provided with a seat receiving the upper portion of the bearing, an adjustable sleeve engaged on the upper portion of the screw and extending through 80 the apertured top and adapted to rotatably support the lower portion of the cabinet, and a locking means carried by the screw between the head and sleeve.

2. The combination with an apertured 85 support and a rotary drum having a depending central trunnion, of a supporting leg comprising a vertical post having a socket in its upper end, a ball seated in the socket, a vertical bolt having a downwardly disposed head formed with a socket for the reception of the upper portion of the ball, an internally threaded sleeve engaged for vertical adjustment on the bolt and receiving the said trunnion in the upper end thereof, 90 and extending through the aperture of the support, and a nut engaged on the bolt below the sleeve.

In testimony whereof, I affix my signature, in the presence of two witnesses.

WILLIAM E. EGBERT.

Witnesses:

D. P. McClure,
R. R. McCormick.
